US0D1113944S

(12) **United States Design Patent** (10) **Patent No.:** **US D1,113,944 S**
Chang (45) **Date of Patent:** **** Feb. 17, 2026**

(54) **DISPLAY SCREEN OR PORTION THEREOF WITH GRAPHICAL USER INTERFACE FOR AN ELECTRONIC HEALTH RECORD**

(71) Applicant: **Khai S. Chang**, Mount Dora, FL (US)

(72) Inventor: **Khai S. Chang**, Mount Dora, FL (US)

(**) Term: **15 Years**

(21) Appl. No.: **29/876,617**

(22) Filed: **May 25, 2023**

(51) **LOC (15) Cl.** **14-04**

(52) **U.S. Cl.**

CLAIM

The ornamental design for display screen or portion thereof with graphical user interface for an electronic health record as shown and described.

DESCRIPTION

FIG. 1 is a front view of a first embodiment of a display screen or portion thereof with a graphical user interface for an electronic health record; and,

FIG. 2 is a front view of a second embodiment of a display screen or portion thereof with a graphical user interface for an electronic health record.

The broken lines showing portions of the graphical user interface form no part of the claimed design.
